UNITED STATES PATENT OFFICE.

EDWARD J. GULICK, OF ELKHART, INDIANA, ASSIGNOR TO C. G. CONN, LTD., OF ELKHART, INDIANA, A CORPORATION OF INDIANA.

MILLING MACHINE FOR CROSS-KNOBS FOR MUSICAL INSTRUMENTS.

Application filed November 1, 1922. Serial No. 593,252.

To all whom it may concern:

Be it known that I, EDWARD J. GULICK, a citizen of the United States, residing in the city of Elkhart, county of Elkhart, Indiana, have invented certain new and useful Improvements in Milling Machines for Cross-Knobs for Musical Instruments, of which the following is a specification.

This invention relates to improvements in the manufacture of instrument bodies and particularly to a machine for milling cross knobs in instrument bodies. The bodies of brass instruments and particularly saxophone bodies are provided on various points with pairs of knobs which are spaced circumferentially but which are located in the same circumferential plane at right angles to the axis of the body. These knobs or projections serve in the finished instrument as bearings for fulcrum pins on which valve levers are secured.

It is an object of the invention to provide a machine of this character by means of which those faces of the cross knobs which are directed towards each other may be suitably milled or treated by some other tool to provide seating surfaces for portions of the pins.

It is also an object of the invention to provide a machine of this character in which cross knobs of varying circumferential spacing may rapidly be finished and in which furthermore, the instrument body is arranged at right angles to the axis of the tool and may be held in this relation in operative position to the tool shaft.

It is also an object of the invention to provide a machine of this character in which the body is supported partly by means of the knobs to be finished and in which the knobs are pressed against seating surfaces by the action of the tool, thereby avoiding the chattering which is otherwise unavoidable unless the part to be finished is tightly clamped in the machine.

It is also an object of the invention to provide a machine of this character in which similar operations may be simultaneously performed on a plurality of instrument bodies and in which a rapid exchange of these instrument bodies for bringing the same body successively into operative relation to different kinds of tools is made feasible.

With these and numerous other objects in view which will become apparent from the following specification, an embodiment of the invention is described in the appended specification and illustrated in the accompanying drawing.

In the drawings:

Fig. 1 is a front elevation of the machine;
Fig. 2 is a horizontal section on line 2—2 of Fig. 1;

Fig. 3 is a similar fragmentary sectional view through the supporting parts;

Fig. 4 shows a supporting element for one of the cross knobs in operative position; Fig. 5 shows the knobs after having been machined, the instrument body being shown in section; Fig. 6 is an enlarged sectional view on line 6—6 of Fig. 3, and Fig. 7 is a similar sectional view on line 7—7 of Fig. 3.

The machine comprises a suitable bed 1 mounted on standards 2 and provided with head stock 3 and a tail stock 4. The head stock 3 may have the driving means which are illustrated by way of example in the present case as a set of step pulleys 5 by means of which a cutter shaft 6 is to be rotated. This cutter shaft, as will be seen from Fig. 1, is detachably mounted in the head stock 3 so as to be rotated by the driving elements 5, and the other end of the shaft is rotatably supported in the tail stock by means of a shank 7 having a socket 8 to receive the reduced pin 9 of said shaft. The shank 7 is removably secured in a socketed pin or bearing sleeve 10 mounted within the hollow bearing box 43 and which can be axially displaced in said box by means of a screw 11 controlled by the hand wheel 12, to enable the insertion or removal of the shank 7 from the sleeve 10, or the engagement and disengagement with the shaft 6.

The bearing box 43 is partially split longitudinally at 44 and the two split parts are provided with the upper and lower aligned bosses 45 and 46, respectively, of which the lower one is tapped. A clamping screw 47 extends into the tapped boss 46 and passes loosely through the upper boss 45, the latter being engaged by the rigid collar 48, said screw being provided with a suitable handle. Upon rotation of the screw 47 the two split portions of the bearing box 43 will be clamped upon and around the sleeve 10, whereby backward displacement of the lat-

ter is prevented when the machine is in operation.

This shaft 6 may be provided with a plurality of cutters or other tools indicated at 5 13 which may have different diameters or different widths, depending upon the formation of the cross knobs which are to be machined thereby. These cutters are in some suitable way fixed to the shaft so as to be 10 exchangeable thereon, and are preferably uniformly spaced from each other in some approved way.

The support for the instrument body is adapted to retain said body in a position in 15 which the cutters 13 may act on a predetermined pair of cross knobs K and may produce in said knobs cut-out portions, as shown in Fig. 5, adapted to permit the insertion of a transverse fulcrum pin or hinge. This pin 20 which is not shown in the drawing, is then located in a plane which is perpendicular to the axis of the body and which at the same time extends thru the axes of the two cross knobs.

25 A support 16 is slidably mounted on the bed 1, longitudinal ribs projecting from the bed into correspondingly shaped grooves in the lower face of the slide 16, Fig. 2. The latter, after having been adjusted to a predetermined position may be held in this adjusted position by a locking pin indicated at 17, Fig. 1, and projecting through the slide 16 and through a portion of the bed.

30 A plurality of bearing structures rise from the slide 16 and may be fixedly or adjustably mounted thereon. These bearing structures 18 comprise, as shown in Figs. 1 and 2, a base plate 19 and a pair of spaced lugs 20 which rise from the base. The lugs carry at 35 their upper ends transverse pins 21 passing through the same and adapted to pivotally support between the lugs, brackets 22 on which the saxophone body S is removably secured.

40 The brackets, as illustrated, particularly in Fig. 3, are composed of a head 25 and a plate 26, arranged at right angle to each other. The head 25 which is substantially vertical has a slanting front face 27 on which a holder bar 28 is secured by fastening screws 29. This bar is U-shaped in cross-section, Fig. 7, and is provided with flanges 30 between which a V-support 31 is slidable in longitudinal direction of the bar 28 and 45 which may be secured at a predetermined position of the holder 28 by means of a screw 32 or some other fastening element.

From this it will be seen that the V-support 31 is readily removable and that different shaped supports may be carried on the bar 28 to accommodate bodies S of different diameter or taper.

50 The head 25 of the bar 28 has a rear surface preferably flush with that of the vertical head 25 of the bracket 22. This head

is provided with a slot 34 through which a portion of the tool 13 may extend in order to enter into proper machining relation with the cross knobs K which are to be finished by the respective tool.

The upper end of the bifurcated head 33 of the holder 28 is furthermore inclined so as to be approximately parallel to the main body of the holder 28, as shown at 35, and is provided with pockets or recesses 36, Figs. 75 4 and 6, in which the ends of the knobs K may be supported.

These recesses of square or rectangular cross-section extend from the inner surfaces of the prongs of the head, and are arranged 80 with respect to the axis of the cutter shaft in such manner that when two cross knobs K are seated on the bottom 37 of the recess, their axes will be in a plane which also contains the axis of the cutter shaft. The free 85 ends of the knobs will rest against a wall surface 37' of the recess which intersects the bottom 37 at right angle. In this position of the knobs the cutting tool 13 will remove parts from the balls b and from the 90 unfinished knobs K, as shown in dotted lines in Fig. 5; the cut out portions being defined by two planes parallel to each other and parallel to the axis of the saxophone body S, both of these planes intersecting 95 the axes of the knobs K at the same angle.

The tool will have a tendency to force the knobs and balls against the seat 37, thereby preventing the chattering which is usually produced in machine work of this character 100 when the elements on which the tool operates are not supported. The tool in the present instance will operate to force the part to be finished against its support and in this way the necessity of firmly securing the 105 saxophone body in place is entirely eliminated.

The bracket 22, while being oscillatably mounted on the pivot pin 21 is normally forced with its head 33 in a direction away 110 from the cutter shaft, owing to the provision of a spring 38 which is interposed between the base 19 and the horizontal part 26 of the bracket. This movement, however, is limited by an adjustable stop illustrated in 115 the embodiment shown, in the form of a screw 39 which engages a tapped opening of the base 19 and which has its head 40 above the plate 26, the screw passing loosely through an opening 41 within said plate. 120 Excessive compression of the spring 38, however, also is prevented, as the screw 39 carries adjustable nuts 42 below the horizontal part 26 so as to limit the swinging movement of this part and thereby the 125 swinging movement of the bracket in either direction.

From Fig. 1, it will be seen that five of these supporting elements for a saxophone body are disposed on a single machine and 130

each of these may be adapted for cooperation with a cutter 13 of different diameter or different width. The cutters are mounted on a shaft 6, the axis of which is stationary.

5 In the operation of the machine the saxophone body is placed on the support 31 in such position that the pair of cross knobs K to be machined, enter the recess 36 and rest on the balls in the corners formed by the 10 bottom 37, and the rear wall 37' of these recesses. During this operation of positioning the saxophone body the spring 38 may force the bracket 22 in counterclockwise direction to bring the horizontal portion 26 into engagement with the adjustable stop 40. After the body has been positioned in this manner and while the machine is in operation, the operator may grip the free end of the holder 28 to force it in clockwise 20 direction about the pivot 21 upwardly until the horizontal part 26 of the bracket is limited by engagement with the stop nuts 42. The saxophone body is then fixedly held temporarily within its support and the operation of machining the elements as illustrated in Fig. 5 may be quickly carried out.

When the operator releases the free end of the bar 28, the bracket 22 is forced by the 30 spring 38 into a position in which the machined parts are removed from the influence of the tool 13 and an excessive machining, therefore, cannot take place in this device.

The operator may now remove the saxophone body from the support 31 and may 35 place it on another support on the same machine with another pair of unfinished cross knobs seated in recesses of another head 33. While in Fig. 1 a single saxophone body is shown as being placed in operative position in the machine, it is obvious that simultaneously a number of bodies may be treated, corresponding to the number of the brackets 22 or any smaller number. It is also obvious that several of the cutters 13 40 may have the same width and diameter so that in different saxophone bodies the corresponding sets of knobs K may be simultaneously treated.

I claim:

50 1. In a cross knob milling machine for instrument bodies, the combination of a tool shaft extending transversely of the axis of the instrument body, and means for supporting said instrument body on the knobs to be machined by said tool.

2. In a cross knob milling machine for instrument bodies, a tool shaft, and means for holding the instrument body in predetermined position with respect to said tool shaft, said means engaging the knobs to be milled.

3. In a cross knob milling machine for instrument bodies, the combination of a tool shaft, a holder in engagement with the body at several points thereof, which are

remote from each other, said holder engaging the knobs to be milled.

4. In a cross knob milling machine for instrument bodies, a bracket supporting the instrument body, said bracket having recesses for receiving the outer ends of the cross knobs to be milled. 70

5. In a cross knob milling machine for instrument bodies, a tool shaft, a bearing, a bracket mounted thereon, a holder for the instrument body on said bracket, the holder having a portion engaging the knobs to be milled and adapted to prevent displacement of said knobs in a direction in which the force of the tool acts thereon. 75

6. In a cross knob milling machine for instrument bodies, a holder for the instrument body, the holder being provided with recesses in which the cross knobs to be milled are seated, the recesses being open on top. 80

7. In a cross knob milling machine, for instrument bodies, the combination of a tool shaft, a bearing, a holder pivoted on said bearing to swing about an axis parallel to that of the tool shaft, a V-shaped projection on the holder adapted to seat the instrument body, and a head on the holder having recesses with rectangularly abutting end surfaces adapted to seat the knobs to be milled. 85

8. In a cross knob milling machine for instrument bodies, the combination of a tool shaft, a holder for an instrument body, the holder having recesses in which the knobs to be milled are seated and having a slot between said recesses adapted for the passage of the tool which is in engagement with the knob to be milled. 100

9. A cross knob milling machine for instrument bodies comprising a tool shaft, a holder for an instrument body disposed transversely of the shaft, and means on the holder for supporting cross knobs of the body in a position with respect to the tool adapted to permit of the machining of both 105 of the cross knobs in a single operation. 110

10. In a cross knob milling machine for instrument bodies, the combination of a tool shaft, a bracket movable in a plane transversely to the axis of the shaft, a holder on said bracket in which a part of the body may be seated, the holder having adjacent the tool shaft recesses for the knobs to be milled, the head also being provided with a slot through which a part of the tool 115 passes in the milling operation for the knobs. 120

11. A cross knob milling machine for instrument bodies, including in combination with a bed, a tool shaft rotatably supported on the bed and having a plurality of tools, bearings longitudinally adjustable on the bed, instrument holders movably supported by said bearings, means for yieldingly forcing the holders in a predetermined direc- 125 130

tion, and means for limiting the movement of said holders.

12. A cross knob milling machine, including in combination with a tool shaft, a bearing, an instrument holder supported by the bearing and engaging laterally projecting parts of the instrument body, the holder ter-

minating in a head having recesses in which associated cross knobs are seated, and means for adjusting the limits of movement of said holder with respect to said bearing. 19

In witness whereof I have hereunto affixed my signature this 28th day of October, 1922.

EDWARD J. GULICK.
